C. S. HAMILTON

PILE FABRIC

Filed March 23, 1927

Inventor,
Charles S. Hamilton.

By his Attorney.
Ramsay Hoguet.

UNITED STATES PATENT OFFICE.

CHARLES S. HAMILTON, OF HARRISON, NEW YORK, ASSIGNOR TO NEW YORK MILLS CORPORATION, OF NEW YORK MILLS, NEW YORK, A CORPORATION OF NEW YORK.

DESIGN FOR A PILE FABRIC.

Application filed March 23, 1927. Serial No. 21,272. Term of patent 7 years.

To all whom it may concern:

Be it known that I, CHARLES S. HAMILTON, a citizen of the United States, and a resident of Harrison, Westchester County, New York, have invented a new, original, and ornamental Design for Pile Fabrics, of which the following is a specification, reference being had to the accompanying drawing, forming a part thereof.

The figure is a plan view of a pile fabric showing my new design.

I claim:

The ornamental design for a pile fabric as shown.

CHARLES S. HAMILTON.
